UNITED STATES PATENT OFFICE.

JOHN C. DOANE, OF HARTFORD, CONNECTICUT, ASSIGNOR TO UNDERWOOD TYPEWRITER COMPANY, OF NEW YORK, N. Y., A CORPORATION OF DELAWARE.

TYPE-WRITING MACHINE.

1,322,548.

Specification of Letters Patent. Patented Nov. 25, 1919.

Application filed February 7, 1917. Serial No. 147,044.

To all whom it may concern:

Be it known that I, JOHN C. DOANE, a citizen of the United States, residing in Hartford, in the county of Hartford and 5 State of Connecticut, have invented certain new and useful Improvements in Type-Writing Machines, of which the following is a specification.

My invention relates to typewriting machines and more especially to escapement mechanism for such machines. It is especially adapted to enable languages, other than English, to be written easily and rapidly on such machines. 10 It is a great desideratum in building typewriting machines for said languages and other special kinds of work, to have the mechanism of such a form that it may be easily built, as far as possible from the 15 standard parts of ordinary machines, and that it may be built by the standard machinery used in the manufacture of standard machines. At the same time the mechanism for effecting the new functions must 20 be strong and not likely to get out of order. 25

My invention is herein disclosed as applied to an Underwood typewriting machine, in which the ordinary feeding and holding escapement dogs usual in such machines, may be either ineffective, or else effective to feed the typewriter carriage either 30 one or two letter-spaces, depending on what typewriter key is depressed.

I have found it possible to attain these 35 objects by utilizing most of the parts of the usual Underwood escapement mechanism, including the usual universal bar which feeds the carriage and actuates the ribbon vibrator.

40 I am able to preserve the simplicity and efficacy of the usual escapement mechanism by causing the ordinary loose dog of the Underwood typewriter to have a variable throw, said throw being controlled by the 45 key which is depressed at the moment. Thus the ordinary typewriter key may operate the usual escapement in the usual manner while a special double width character key may cause the loose dog to have an 50 extra throw; while a silent key, such as an accent key, may shift to ineffective position an interponent which normally is in effective position, between the universal bar and the feeding and holding dog mechanism. 55 Thus a single universal bar is able to fulfil

all the functions hitherto thrown on it together with the added function of feeding the carriage an extra space for an extra wide character.

Other features and advantages will here- 60 inafter appear.

In the accompanying drawings,

Figure 1 is a sectional side view of an Underwood typewriting machine, showing my invention as applied thereto. 65

Fig. 2 is a sectional plan view of the escapement mechanism, at a point near the bottom of the ordinary escapement wheel.

Fig. 3 is a skeleton perspective view of many of the principal parts shown in Fig. 1. 70

Fig. 4 is a front view of the escapement mechanism in the position in which it normally holds the typewriter carriage.

Fig. 5 is a similar view, showing the position of the parts when a key is depressed 75 to cause a single step movement of the carriage.

Fig. 6 is a similar view, but showing the parts positioned when a key is depressed which gives the carriage a two-step move- 80

ment. In the Underwood typewriting machine, the usual character alphabet keys 1, when depressed, carry down key-levers 2, and thereby each key causes its own type-bar 3 85 to be swung upward, so that its type 4 prints against a platen 5 on a carriage 6. Each type-bar 3 is connected to its key-lever 2 by means of the usual bell-crank 7, which engages with a pin 8 on the key-lever, and 90 swings up the type-bar by means of a pin 9 running in a cam slot 10 on the type-bar.

The typewriter carriage 6 is normally under tension drawing it to the left by means of the usual spring barrel 11, which 95 is connected to the carriage by a band 12, but the carriage is normally held against the tension of the spring 11 by an escapement wheel 13. This is prevented from turning by a feeding dog 14, and is connected by the usual spring pawls 17 to a pinion 15 which meshes with a rack 16 connected to the typewriter carriage. This permits the carriage to be drawn back while the escapement wheel 13 remains engaged 100 with the dog 14.

Every time a key 1 is depressed to print, it releases the carriage from the loose or feeding dog 14 by rocking a fixed or holding dog 18, on which the feeding dog is 110

pivoted, so that the feeding dog 14 is pushed rearwardly clear of the escapement wheel 13, while the face 19 of the fixed dog engages the same tooth of the escapement 5 wheel 13 and holds the wheel so the carriage makes practically no movement if the escapement is properly adjusted. The freeing of the fixed dog 14 from the escapement wheel 13 permits the usual spring 20 to 10 draw said dog to the left until it is arrested by a shiftable stop 21. Normally this shiftable stop 21 stands in the position seen in Fig. 2, in which an extension 22 of the shiftable stop 21 arrests the feeding dog 14 15 in the position shown in Fig. 5. This shifting of the dogs is accomplished by the usual universal bar or frame 23, which is pivoted on idle rockers 24 at the rear of the machine, and which, at the front, includes a segment 20 extension 25, which is struck by a heel 26 on the rising type-bar, with the result that the universal bar 23 moves backward against the tension of a spring 27 which normally draws it forward. In thus moving backward, a cross-bar 28, forming part of the 25 universal frame 23, strikes a pin or lug 29 on the holding dog 18 by means of an interponent which will presently be described, and thus rocks said dog backward in the 30 manner described, it being for this purpose pivoted on the usual bearings 30.

When the key 1 is released, it rises and allows the spring 27 to draw forward the universal bar, and this causes the holding dog 35 18 to be rocked forwardly, partly because of the spring 20 which is anchored considerably forward of the pivots forming the bearings 30 on a forwardly-extending bracket 31. The tension of the spring bar- 40 rel 11 can then draw the typewriter carriage along to the left, because the escapement wheel 13 is no longer held by the holding dog 18, but is free to be moved to its right-hand position against the tension of its 45 spring 20. The limit of its throw to the right is determined by an arm or lug 32 extending rearwardly from the holding dog.

If, however, a special character key 33 is caused to print a character which requires 50 the typewriter carriage to feed more than a single step, said key operates connections whereby the lug 22 is moved to ineffective position, thus permitting the feeding dog 14 to be drawn farther to the left on the de- 55 pression of the key, with the result that on the rise of the key the typewriter carriage will be able to move the feeding dog farther, Fig. 6, and therefore have a longer step motion. To effect this, each key 33 is 60 connected to shift the lug 22, doing this by means of a link 34 detachably hooked into a slot 35 in its key-lever. To enable the lug 22 to be shifted, it is formed as part of a 65 sliding plunger 36, which is normally pressed forwardly by a spring 37, coiled

around the stem of the plunger, and the plunger is adapted to be thrust rearwardly by means of an upstanding rock arm 38, fast on a transverse shaft 39. Thus, every time the shaft 39 is rocked to carry its rock 70 arm 38 rearwardly, the plunger 36 is moved rearwardly to carry the lug 22 to a position clear of the feeding dog 14, and to bring a cut-away step portion 40 of the plunger opposite said feeding dog. In order to rock 75 the shaft 39, each link 34 is hooked by means of a slot 41^a to a headed pin 41 on the end of a rock arm 42, which is fast to said shaft 39. Thus, the connections are such that the depression of the key 33 will draw down 80 the link 34 to draw down the rock arm 42, thus rocking the shaft 39, swinging the rock arm 38 rearwardly, and bringing the cut-away portion 40 of the plunger 36 into effective position to arrest the feeding dog 14. 85 In order to normally hold the arm 38 in ineffective position, the shaft 39 is provided with a coil spring 43, which holds the rock arm 38 clear of the plunger 36, and also holds the rock arms 42 upward, in which 90 position their headed pins 41 catch in narrow portions of the slots 41^a, so that the pins cannot escape from the slots. To permit ready assembly of the mechanism, the slots 41^a are provided with enlarged extensions 44 95 which can be hooked over the headed pins 41, thus permitting the narrow portions of said slots 40 to be securely caught by the heads of the pins 41. The spring 43, by holding the rock arm 42 upward, also serves 100 to keep the ends of the hooks caught in the slots 35 of the key levers; this being so because the key-levers cannot rise above their normal positions, their throw being limited by the usual stop-bar 46 which is effective on the type-bars. 105

It will be remembered that in the usual Underwood machine, the universal bar 23 is not moved until well on toward the end of the key depression, and the connections 110 between the two-step feeding keys 33 and the plunger 36 are advantageously such that the lug 22 remains effective to cause the normal feeding movement of the carriage until about the time the escapement mechanism 115 begins to release the feeding dog 14, thus allowing a key which has been erroneously partly depressed to be restored without catching the feeding dog on the cut-away portion 40 of the plunger 36. 120

In order to permit the feeding dog 14 to swing into position to catch the escapement wheel 13 when it has swung back for a two-step feeding motion, the back face of the feeding dog 14 is cut away at 47 to permit 125 it to slip behind the adjacent tooth of the escapement wheel 13, as is necessary in preparing for a two-step feeding motion. It will be noted that there is only one shaft 39 and one arm 38 universal to all the two- 130

step feeding keys 33, and that each of said keys 33 has its own link 34 and its own rock arm 42.

It will be noted that my invention makes it possible to retain the advantages of the usual cam face 19 of the holding dog 18 of the Underwood machine, which makes the escapement thereof so accurate and rapid. For convenience in assembling, the spring 10 43 engages the shaft 39 by a collar including a set screw 49, and the rock arms 42 are held in place by similar set screws 50. There is also provided a set screw 51 for holding the rock arm 38 in place. The 15 spring 37 pushes the plunger 36 forwardly by bearing against a collar 52 thereon, which is also settable by a set screw 53. The collar is provided with a flat face which bears against a bracket 54 in which the plunger 20 slides, thus holding the plunger 36 from rotation and insuring that the lug 22 will present its proper face to the feeding dog 14.

The depression of a silent character key 55 may cause its type bar to actuate the universal bar or segment 25 in the usual manner, but said silent key before it prints, moves to ineffective position an interponent 56, which normally stands between the universal frame 23 and the dog-operating pin 29 to thereby operate the dog rocker 18. To effect this, a key lever 57 of the silent key 55 is provided with an opening 58 which is engaged by the hooked end of a link 59, said link being adapted to shift the interponent 56 down to a position below the cross-bar 28. To effect this, the link 59 is hooked by an elongated slot over a headed pin 60, forming part of a rock arm 61 on a universal shaft 62, said shaft also having 30 fast thereto a rock arm 63 which engages the lower part of the interponent 56. The result is that whenever any key 55 is depressed, its link 59 rocks the universal shaft 62, thereby drawing down the interponent 45 56 to beneath the cross-bar 28 so that the cross-bar 28 will rock idly so far as the holding dog 18 is concerned.

On the rise of the key, the interponent 56 rises to effective position, being lifted upwardly by a weight 65 on a forward extension of the rock arm 63. A spring 67 also constantly tends to lift the interponent to effective position. The arm 63 operates the interponent 56 by means of a lug 68 formed 55 on the interponent which underlies a turned-over extension 69 on the arm 63.

The universal bar 23 is provided with the usual actuator frame 70 including a slot 71, on which rides a pin 72 of the usual actuator lever 73 which is effective to lift the ribbon carrier 74 in the usual manner at every key stroke.

It will be observed, that the rock shafts 39 and 62 may be journaled in the same 65 bracket 75, and that the links 59 and 34 may

be identical in form except for their length, and hook on their respective key-levers and headed pins in an identical manner, thus rendering the assembling of the machine cheap and the making of its parts equally 70 cheap.

Variations may be resorted to within the scope of the invention, and portions of the improvements may be used without others.

Having thus described my invention, I 75 claim:

1. In a typewriting machine, the combination with a traveling carriage and character printing keys, of a single universal bar operated by said keys and having a uniform 80 throw, an escapement mechanism for said carriage, an interponent operated by said universal bar for operating said escapement mechanism, an escapement wheel forming part of said escapement mechanism, a dog 85 rocker including a fixed or holding dog and a loose dog also forming part of said escapement mechanism, said loose dog normally holding said carriage by said wheel, means whereby the universal bar causes the 90 holding dog to hold said carriage and release the loose dog, a spring for drawing said loose dog to position to enable the carriage to be fed along, a bar universal to certain of said keys, a connection whereby the 95 last-named universal bar, when operated, moves said interponent to ineffective position, and a single stop selectively moved by others of said keys for selectively determining whether said loose dog shall be drawn 100 back to position to effect feeding of the carriage one or more letter spaces.

2. In a typewriting machine, the combination with a traveling carriage and character printing keys, of a single universal bar universal to said keys, an escapement mechanism, an interponent operated by said universal bar for operating said escapement mechanism, certain of said keys printing characters of extra width, a member universal to said extra width character keys timed to act before said bar, a loose dog forming part of said escapement mechanism normally holding the carriage and adapted to be drawn back on the depression of a key, 105 a stop for variably arresting said loose dog and normally occupying one position, a universal shaft operated by certain other keys, a connection whereby the universal shaft, when operated, makes said interponent ineffective, and means operated by said universal member for shifting said stop to increase the throw of said loose dog.

3. In a typewriting machine, the combination with character printing keys, of a traveling carriage, an escapement for said carriage, a single universal bar for said keys, a ribbon vibrator operated by said universal bar, and means selectively operated by said keys for making said universal 125 130

bar ineffective or effective to feed said carriage, one space, or effective to feed said carriage a plurality of spaces.

4. In a typewriting machine, the combination with character printing keys, of a traveling carriage, an escapement for said carriage, a single universal bar for said keys, a ribbon vibrator operated by said universal bar, means selectively operated by said keys for making said universal bar ineffective or effective to feed said carriage one space, or effective to feed said carriage a plurality of spaces, said means including a member universal to certain of said keys for rendering said universal bar ineffective, and also including an escapement mechanism to feed said carriage, and a second member universal to only certain of the remaining keys to cause said escapement mechanism to feed said carriage the greater distance.

5. In a typewriting machine, the combination with a traveling carriage and character printing keys, of an escapement mechanism for said carriage, a universal bar having an identical throw for all of said keys, and means selectively operated by groups of said keys for making said universal bar effective to feed said carriage or to feed said carriage an extra space or to be ineffective on said carriage.

6. In a typewriting machine, the combination with a traveling carriage and character printing keys, of an escapement mechanism for said carriage operated by said keys, a universal bar universal to all the keys for said escapement mechanism, an interponent whereby the universal bar actuates the escapement mechanism, a fixed and a loose dog for said escapement mechanism, a fixed stop against which said loose dog normally rests to hold the carriage, a stop limiting the throw of said loose dog when loose, means whereby one group of said keys makes said interponent ineffective, and means whereby another group of said keys shifts said last-named stop to vary the idle throw of said loose dog.

7. In a typewriting machine, the combination with a traveling carriage and character printing keys, of an escapement mechanism for said carriage operated by said keys, a universal bar universal to all the keys for said escapement mechanism, an interponent whereby the universal bar actuates the escapement mechanism, a fixed and a loose dog for said escapement mechanism, a fixed stop against which said loose dog normally rests to hold the carriage, a stop limiting the throw of said loose dog when loose, means whereby one group of said keys makes said interponent ineffective, and means whereby another group of said keys shifts said last-named stop near the end of a key stroke to vary the idle throw of said loose dog.

8. In a typewriting machine, the combination with a traveling carriage and character printing keys, of a universal bar operated by said keys, a member universal to certain only of said keys, an escapement mechanism for said carriage, an interponent for said escapement mechanism shiftable by said last named keys, a member universal to said last-named keys for so shifting said interponent, a stop for varying the throw of the escapement mechanism, and a member universal to certain only of the remaining keys for varying said escapement throw.

9. In a typewriting machine, the combination with character printing keys and type-bars operated thereby, of a universal bar operated by said type-bars as they approach the platen, a rock shaft universal to certain of said keys and operated thereby, a rock shaft universal to certain other of said keys, certain of said keys being ineffective on either rock shaft, a stop variably settable by one rock shaft for varying the escapement, and an interponent shiftable by the other rock shaft making the escapement ineffective.

10. In a typewriting machine, the combination with character printing keys and type-bars operated thereby, of a universal bar operated by said type-bars as they approach the platen, a rock shaft universal to certain of said keys and operated thereby, a rock shaft universal to certain other of said keys, certain of said keys being ineffective on either rock shaft, a stop variably settable by one rock shaft for varying the escapement, an interponent shiftable by the other rock shaft making the escapement ineffective, and a single bracket on which said rock shafts are journaled.

11. In a typewriting machine, the combination with a traveling carriage and character-printing keys, of an escapement for said carriage, a universal bar operated by said keys near the end of their effective stroke, a loose dog forming part of said escapement and normally holding the carriage, a member shiftable to vary the throw of said dog when it releases the carriage, levers for said keys, a universal rod adjacent said key-levers, links for connecting said universal rod to certain of said keys, and a connection from said universal rod for operating said member.

12. In a typewriting machine, the combination with a traveling carriage and character-printing keys, of an escapement for said carriage, a universal bar operated by said keys near the end of their effective stroke, a loose dog forming part of said escapement and normally holding the carriage, a member shiftable to vary the throw of said dog when it releases the carriage, levers for said keys, a universal rod ad-

5 jacent said key-levers, links for connecting said universal rod to certain of said keys, a connection from said universal rod for operating said member, a second rod adjacent said key-levers, an interponent between said universal bar and said escapement, means for making said interponent effective or ineffective by said second rod, and links adapted to connect said second rod to certain of said keys.

10 13. In a typewriting machine, the combination with a traveling carriage and character-printing keys, of an escapement mechanism for said carriage operated by said keys, a bar universal to said keys for operating said escapement mechanism, a rocking bar extending across said keys and comprising extending arms, hooks adapted to engage said keys and also said rocking bar-20 arms to rock said bar, so that it forms a member universal to certain of said keys, and means operated by said rocking bar for varying the feed of the carriage by said escapement mechanism.

15 14. In a typewriting machine, the combination with a traveling carriage and character-printing keys, of an escapement mechanism for said carriage operated by said keys, a bar adjacent said keys, rock-arms 30 upon said bar, headed pins upon said rock-arms, hook members adapted to engage said keys comprising slots adapted to hook over said headed pins, and a torsional device for maintaining said bar in position to hold 35 said hooks engaged with said keys.

20 15. In a typewriting machine, the combination with a traveling carriage and an array of character-printing keys having perforations similarly placed, of a plurality of universal rods above said keys, operating extensions for said universal rods, removable hooks extending from said perforations to said extensions to enable the keys to selectively operate said rods, an escapement mechanism varied by said rods, and a single universal bar common to all of said keys for operating said escapement mechanism.

25 16. In a typewriting machine, the combination with a traveling carriage and an array of character-printing keys having perforations similarly placed, of a plurality of universal rods above said keys operating extensions for said universal rods, removable hooks extending from said perforations to said extensions to enable the keys to selectively operate said rods, an escapement mechanism varied by said rods, and a single universal bar common to all of said keys for operating said escapement mechanism, 50 one of said rods adapted to cause said escapement mechanism to variably feed the carriage, and the other rod adapted to make

said escapement mechanism ineffective to feed the carriage.

17. In a typewriting machine, the combination with a traveling carriage and an array of character-printing keys having perforations similarly placed, of a plurality of universal rods above said keys, operating extensions for said universal rods, removable hooks extending from said perforations to said extensions to enable the keys to selectively operate said rods, an escapement mechanism varied by said rods, a single universal bar common to all of said keys for 75 operating said escapement mechanism, a single bracket at each side of the machine in which said rods are journaled, headed pins on said extensions engaging key-shaped perforations in said hooks, and devices adapted to hold said pins in said hook-perforations to hold the hooks in place.

18. In a typewriting machine, the combination with a traveling carriage and an array of character-printing keys having perforations similarly placed, of a plurality of universal rods above said keys, operating extensions for said universal rods, removable hooks extending from said perforations to said extensions to enable the keys to selectively operate said rods, an escapement mechanism varied by said rods, a single universal bar common to all of said keys for 80 operating said escapement mechanism, a loose dog normally holding said carriage 85 and forming part of said escapement mechanism, a spring adapted to give said loose dog a throw when it releases said carriage, a stop adapted to be shiftable by one of said rods to vary the throw of said dog, and 90 an interponent between said universal bar and said dog adapted to make the universal bar ineffective on the dog.

19. In a typewriting machine, the combination with character-printing keys and type-bars operated thereby, of a universal bar operated by said type-bars as they approach the platen, a universal rod adjacent said universal bar, operating extensions for said universal rod, removable hooks extending from perforations in certain of said keys to said rod to enable the keys to selectively operate said rod, an escapement mechanism including a normally effective loose dog, a spring adapted to draw on said loose dog when it is made ineffective, a rock-arm on said rod, and a stop movable by said rock-arm adapted to selectively control the throw of said loose dog when ineffective.

JOHN C. DOANE.
